UNITED STATES PATENT OFFICE.

FRANK J. GIBBONS, OF WORCESTER, MASSACHUSETTS.

DETACHABLE ARCH SUPPORT.

Application filed August 27, 1926. Serial No. 132,008.

This invention relates to an arch support adapted to be detachably mounted on the outside or bottom of the sole of a shoe.

The principal objects of the invention are to provide an arch support located outside the shoe so that it will support the shank of the sole across the foot and not merely at one point and yet located at the center preferably where the difficulty usually lies; to provide a support of this character which can be detachably mounted so that it can be removed very easily for relief of the wearer, especially when he is first getting used to it, and so that it cannot shift from one position to another and become detached accidentally; and also to provide a construction which is so easily and simply attached that the ordinary wearer can take it off and put it on without assistance; and to provide a construction in which the rubber of the support is permanently vulcanized in position and absolutely prevented from coming off the supporting plate at any time during its wear. The invention also involves details of construction as will appear.

Reference is to be had to the accompanying drawings in which

Fig. 1 is a side view of a shoe with a preferred form of this arc support in position thereon;

Fig. 2 is a central sectional longitudinal view of the same;

Fig. 3 is a bottom plan view of the arch support in position on the shoe;

Fig. 4 is a similar view of the plate on the shoe with the arch support entirely removed;

Fig. 5 is a top plan view of the detached arch support;

Fig. 6 is an enlarged front edge view;

Fig. 7 is a perspective view of the plate on the shoe;

Fig. 8 is a perspective view of the detachable metal plate;

Fig. 9 is a perspective view of the rubber pad; and

Fig. 10 is a plan of the holding loop.

This invention relates to the class of arch supports in which a rubber pad 10 is mounted on the bottom of the in-sole of the shoe.

The arch support is provided with a horizontal portion along the bottom and gradually slanting or curving upwardly along the front.

This rubber pad is vulcanized in position on a supporting plate 11 and held there permanently by loops 13 bent up from the

supporting plate and having passages through them for receiving the rubber. Thus this plate is made in a single sheet of metal punched into its final position in a very simple manner. The plate 11 is provided with a tongue 15 in the center in front and with two sharpened edges 16 at the sides thereof for holding it in place. It is also provided with up-turned hooks 17 and 18 at the rear.

The holding device consists of a wire loop 19 for engaging a stationary plate 25. It is located in a horizontal plane and has an offset 20 at the center and two crossing free spring ends 21. These two ends project under the center hook 18 and it is held in position at the end by the other two hooks 17.

The device is held on the shoe by a stationary plate 25 of sheet metal which has an upwardly extending projection 26 at the heel for engaging in the offset 20 of the wire fastening device. It is also provided with two integral hooks 27 at the sides of the front end for receiving the sharp edges 16 and holding the plate 11 at that end pivotally so that it can be detached. These hooks are spaced apart a certain distance to receive the forward portion 15 of the first-named plate. This plate is nailed or permanently secured to the sole of the shoe at the shank projecting forward from the heel as shown.

In putting the parts together, the forward central tongue 15 of the detachable plate 11 is thrust between the two hooks 27 with the knife edges under these hooks. Then the rear end is forced down so that the wire catch will yield and move in under the projection 26 at the rear of the stationary plate 25. Then it is firmly and securely fixed in position and cannot get detached accidentally but only by the use of a tool, as a knife blade or screw driver.

This arch supports the shank at the proper position and yet does not furnish a lump sticking up into the shoe on the inside. The sides of the shank are supported by the sole in the usual way with as much elasticity as the sole itself furnishes.

It will be noticed that this support is not only very easily detachable, but it is detachable in a direction away from the sole of a shoe, not by any longitudinal sliding motion through guides which would be apt to get rusted or filled with dirt and dust. The

device can always be removed irrespective of the condition of the bottom of the shoe.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:—

1. In an arch support, the combination with a plate adapted to be fixed to the sole of the shoe at the shank and to project against the front of the heel, said plate having means at the front thereof for pivotally engaging the front of an arch support, and means at the rear thereof at the front of the heel for detachably connecting it with the rear of the arch support.

2. In an arch support, the combination with a plate adapted to be fixed to the sole of the shoe at the shank and to project against the front of the heel, said plate having means at the front thereof for pivotally engaging the front of an arch support, and means at the rear thereof at the front of the heel for detachably connecting it with the rear of the arch support, of an arch support comprising a second plate having means for connecting it with the first plate at the front and a yielding latch detachably connected with the projection at the rear.

3. In an arch support, the combination with a shoe, and a plate on the bottom of the shank thereof fixed thereto, of a plate adapted to be pivotally connected with the

front of said plate so as to swing about the front of it into contact with it throughout its length, means for detachably securing the second plate to the first at the rear thereof, means for preventing any motion of the movable plate after it is attached, and a rubber supporting member vulcanized permanently to the detachable plate.

4. In an arch support, the combination with a sheet metal plate having perforations therethrough and the middle of said perforations bent outwardly to form straps at a distance from the plate, of a rubber pad vulcanized to and through said projections in the plate, whereby the material of said plate projects into the pad itself and permanently holds it in position.

5. As an article of manufacture, a detachable support for the outside of the shank of a shoe comprising a metal plate having means at the front edge for holding it to a permanent part of the shoe and permitting of its swinging about a forward transverse axis, said plate having two hooks at the rear bent up from it near the sides and one between them and spaced from them, and a wire fastening device bent around the pair of hooks and having its ends crossing each other and extending around under the center hook for holding it in position and giving it the necessary yielding action to permit it to be secured under a permanent projection at the heel of the shoe.

In testimony whereof I have hereunto affixed my signature.

FRANK J. GIBBONS.
